BOTTLE COOLER

Filed Dec. 13, 1935

FIG. 1.

FIG. 2.

INVENTOR:
RALPH MATTICK
BY *Henry Kneale*,
ATTORNEY

UNITED STATES PATENT OFFICE

99,133

DESIGN FOR A BOTTLE COOLER

Ralph Mattick, St. Louis, Mo., assignor to General Metal Products Company, St. Louis, Mo., a corporation of Missouri

Application December 13, 1935, Serial No. 60,048

Term of patent 14 years

To all whom it may concern:

Be it known that I, Ralph Mattick, a citizen of the United States, residing at St. Louis, in the State of Missouri, have invented a new, original, and ornamental Design for Bottle Coolers, of which the following is a specification, reference being had to the accompanying drawing, forming part thereof.

In the accompanying drawing, Fig. 1 is a front perspective of a bottle cooler and Fig. 2 is a rear perspective of a bottle cooler embodying my new design.

I claim:

The ornamental design for a bottle cooler, as shown.

RALPH MATTICK.
